FIG. 3

FIG. 4

FIGURE 1 is a perspective view of an emergency lighting unit showing our new design with one of the adjustable lamps shown in an alternate position; and

FIGURE 2 is a side elevational view thereof;

FIGURE 3 is a front elevational view thereof; and

FIGURE 4 is a top plan view thereof.

The undisclosed rear is substantially plane and unadorned.

The dominant features of our design reside in the portions shown in full lines.

We claim:

The ornamental design for an emergency lighting unit, as shown and described.
